UNITED STATES PATENT OFFICE

NILS ERIK WAHLBERG, OF KENOSHA, WISCONSIN, ASSIGNOR TO THE NASH MOTORS COMPANY, OF KENOSHA, WISCONSIN, A CORPORATION OF MARYLAND

MOTOR-COOLING SYSTEM

Application filed January 25, 1928. Serial No. 249,216.

This invention relates to improvements in internal combustion motors, and has for its principal object to provide an improved construction thereof utilizing a spacer of aluminum or similar metal having high heat conductivity adjacent the cylinder head but disposed between the main bore of the cylinder and the cylinder head and valve mechanism, so as to take advantage of the superior heat-dissipating qualities of said spacer.

10 The invention may best be understood by reference to the accompanying drawing, in which

15 Figure 1 shows an upper fragmentary portion of a motor cylinder block in vertical cross section to which my invention has been applied.

20 Figure 2 is a plan view of a spacer, in part section, constructed in accordance with my invention.

Figure 3 is a side view, in part section, of the spacer shown in Figure 2.

In the drawings, 10 denotes a multi-cylinder casting of the usual form, such as cast iron or 25 its equivalent, including an integral water jacket 11. Pistons 12—12 of any approved form, such as cast iron, or aluminum alloy, are mounted in the cylinders, as usual. A cylinder head 13 also of cast iron is provided, 30 in the form shown said head including a water jacket 14 and valve seats 15, 15 for valves 16, 16 of the overhead type. The operating mechanism for the valves is omitted as it forms no part of the invention.

35 Referring now more particularly to the novel features of my invention, I provide a spacer 20 of substantial height inserted between the upper end of the main cylinder body 10 and the cylinder head 13. This spacer is preferably made of aluminum or similar metal having a relatively high heat conductivity, although such metals as a rule lack the strength and wear-resisting qualities of cast iron or the like, usually utilized in cylinder 40 castings. Furthermore, such metals ordinarily have a different coefficient of expansion so they cannot ordinarily be used successfully for bearing parts in combination with cylinder castings of ordinary construction.

50 In carrying out my present invention, I

make use of the cooling properties of the aluminum, or the like, without its attendant disadvantages by terminating the main cylinder body 10 substantially at the upper limit of movement of the pistons 12—12, so that the latter have their usual bearing engagement with the cylinder walls throughout their stroke. Furthermore, the valve seats and valve mechanism are mounted as usual in the cylinder head 13 so that the standard valve construction is mounted in the cylinder head casting, as usual.

The water jackets 11 and 14 of the cylinder body and cylinder head, respectively, communicate with water passages 21 extending through the aluminum spacer 20, so that the latter passages form a part of the water cooling system of the motor. With this arrangement, the superior strength and wear-resisting qualities of the usual cylinder casting 55 metal are retained where needed, but the heat is conducted more rapidly from the combustion chambers through the inner walls of the aluminum spacer and carried away by the water, than is the case with ordinary full cast-iron cylinder construction, thus resulting in more efficient cooling of the combustion chamber than has heretofore been practical.

The construction above described is especially advantageous in motors of the valve-in-head type, wherein the available cooling area is limited by the provision of valves and valve seats, but manifestly it can also be applied to L-head or other types of motors to substantial advantage without in any way affecting 80 standard features of construction of the valve mechanism and associated parts.

I claim as my invention:

1. In a motor and in combination with a cylinder casting and detachable cylinder head 90 casting, a metal spacer of relatively high heat conductivity of the order of aluminum inserted between said cylinder casting and cylinder head and forming a substantial part of the wall area of the combustion chamber 95 above the cylinder casting.

2. In a motor and in combination with a cylinder casting and a detachable cylinder head casting having valves and valve operating mechanism carried thereby, a metal 100

spacer of relatively high heat conductivity of the order of aluminum inserted between said cylinder casting and cylinder head and forming a substantial part of the wall area of the combustion chamber above the limit of movement of the piston within said cylinder.

3. In a motor and in combination with a cylinder casting, and a detachable cylinder head casting both provided with water jackets, a metal spacer of relatively high heat conductivity of the order of aluminum inserted between said cylinder casting and cylinder head and forming a substantial part of the wall area of the combustion chamber above the cylinder casting, said spacer having apertures therethrough communicating with said water jackets and forming part of the water cooling system of said cylinders.

4. In a motor and in combination with a cylinder casting, and a detachable cylinder head casting, both of cast iron, an aluminum spacer inserted between said cylinder casting and cylinder head and forming a substantial part of the wall area of the combustion chamber above the limit of movement of the piston within said cylinder.

Signed at Kenosha, Wis., this 17th day of January, 1928.

NILS ERIK WAHLBERG.
